United States Patent

Des. 238,854

Patented Feb. 17, 1976

238,854

BOTTLE OR SIMILAR ARTICLE

William J. Britt, Greenville, S.C., assignor to Morton-Norwich Products, Inc., Norwich, N.Y.

Filed Apr. 18, 1974, Ser. No. 461,947

Term of patent 14 years

Int. Cl. D9—01

U.S. Cl. D9—144

FIG. 3

FIG. 1

FIG. 2

FIG. 4

FIG. 1 is an elevational view of a bottle or similar article showing my new design;

FIG. 2 is an elevational view looking from the right of FIG. 1, the opposite side being a mirror image of FIG. 2;

FIG. 3 is a top plan view; and

FIG. 4 is a bottom plan view thereof.

I claim:

The ornamental design for a bottle or similar article, as shown and described.
